[57] CLAIM

The ornamental design for spout, substantially as shown and described.

DESCRIPTION

FIG. 1 is a top plan view of a spout incorporating my new design.

FIG. 2 is a front elevational view thereof.

FIG. 3 is a right side elevational view thereof, the left side being a mirror image of the right side shown.

FIG. 4 is a rear elevational view thereof.

The fragmentary broken line showing of a sink in FIGS. 2, 3 and 4 is for purposes of illustration only and forms no part of the claimed design.
